US00D821809S

(12) **United States Design Patent** (10) **Patent No.:** **US D821,809 S**
(45) **Date of Patent:** **** Jul. 3, 2018**

(54) **LID**

(71) Applicant: **YETI Coolers, LLC**, Austin, TX (US)

(72) Inventors: **Mark Rane**, Austin, TX (US); **Dustin Bullock**, Austin, TX (US); **Ian Cunningham**, Austin, TX (US)

(73) Assignee: **YETI Coolers, LLC**, Austin, TX (US)

(**) Term: **15 Years**

(21) Appl. No.: **29/587,379**

(22) Filed: **Dec. 13, 2016**

(51) LOC (11) Cl. **07-01**

(52) U.S. Cl.

USPC **D7/396.2; D9/449**

(58) **Field of Classification Search**

USPC D3/202, 318, 298; D7/213, 300, 300.1,
D7/312–314, 316–319, 321, 322, 387,
D7/392, 392.1, 396.2, 396.3, 397, 398,
D7/510, 533, 394, 511; D9/434–436,
D9/440, 443, 447, 499, 454, 448–450

CPC B65D 47/065; B65D 47/066

Assistant Examiner — Darcey E Heflin

(74) *Attorney, Agent, or Firm* — Banner & Witcoff, Ltd.

(57) **CLAIM**

The ornamental design for a lid, as shown and described.

DESCRIPTION

FIG. 1 is a top, front, left perspective view of a lid showing our new design in an open position;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, left perspective view of a lid showing our new design in a closed position;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines showing the remainder of the lid are for environmental purposes only and form no part of the claimed design.

1 Claim, 13 Drawing Sheets
